(57) **CLAIM**

The ornamental design for a constellation solar light, as shown and described.

DESCRIPTION

FIG. 1 is a perspective view of a constellation solar light in accordance with my invention;

FIG. 2 is a side view of the constellation solar light shown in FIG. 1;

FIG. 3 is a top view of the constellation solar light shown in FIG. 1; and,

FIG. 4 is a bottom view of the constellation solar light shown in FIG. 1.

The broken lines shown on the drawing are for illustrative purposes only and form no part of the claimed design.
